UNITED STATES PATENT OFFICE.

JOSEPH R. WITZEL, OF TACONY, PENNSYLVANIA.

BUILDING CONSTRUCTION.

1,378,520.

Specification of Letters Patent. Patented May 24, 1921.

Application filed June 22, 1920. Serial No. 890,749.

To all whom it may concern:

Be it known that I, JOSEPH R. WITZEL, a citizen of the United States, residing at Tacony, in the county of Philadelphia and State of Pennsylvania, have invented certain new and useful Improved Building Constructions, of which the following is a specification.

This invention has for an object to provide an improved building construction in which tension and tensile reinforcements are employed whereby the walls of a building are made perfectly rigid and unyielding to strain in all directions so that the center of a wall is as strong as the abutments. Another object is to provide a structure of maximum strength in which a minimum amount of material is employed.

With these and other objects in view the invention consists of the improvements hereinafter described and finally claimed.

The nature, characteristic features and scope of the invention will be more fully understood from the following description taken in connection with the accompanying drawings forming part thereof, and in which there is shown in perspective a view of a unit employed in the erection of a building illustrating the application thereto of a reinforcement embodying features of the invention.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

According to the present invention I may construct of skeleton construction units as shown for the building of houses, ships, bridges, garages, vaults, safes, refrigerators, fences, columns and many other structures and employ in such structures the tensile reinforcement about to be described. In the case of a skeleton unit the main supporting frame is designated 10, secured to which are a plurality of vertically and horizontally disposed wires, rods, pipes or equivalent mediums, wires 11 being shown in

the drawings for illustrative purposes. These mediums are tightened to the proper tension so that the frame is perfectly rigid and unyielding to strain in all directions 60 and so that the center of a wall is as strong as the abutments. For illustrative purposes turnbuckles 12 are shown as a means for placing the wires under tension although obviously other methods of securing 65 tension may be employed. With the reinforcement in proper position under tension suitable plastic material may be inclosed, cast or pressed with respect thereto as is well understood in the art, or slabs of suitable 70 material may be secured to said frame which slabs of course cover the reinforcement. The units may be fitted together to form a suitable structure.

The above principle of tension and tensile reinforcement is applicable for repair as well as new work. In the case of an old structure, for instance a frame building, my improved reinforcement may be applied to the old structure (used as a supporting 80 frame) and a covering of suitable material applied to the reinforcement.

According to the present invention, I may make complete or partial structures; plane, recessed or raised surfaces; molded, cast or 85 pressed constructions or sheet coverings; units or integral structures and screened apertured work. In the latter case the covering can be omitted in places thus leaving 90 apertures across which extend the reinforcements to provide a screen. In certain cases the nails, screws, staples, cleats, or other devices employed to hold together a supporting frame need not be driven home so the exposed ends can be utilized as means 95 upon which to draw taut the ends of wires to provide tension. Of course, cement or other material applied to reinforcement covers said exposed mediums. The wires 11, where they cross one another may be se- 100 cured by means of wire or the like 16.

It will now be apparent that I have devised a novel and useful construction which embodies the features of advantage enumerated as desirable in the statement of the 105 invention and the above description and while I have in the present instance shown and described the preferred embodiment thereof which has been found in practice to give satisfactory and reliable results, it is 110 to be understood that the same is susceptible of modification in various particulars

without departing from the spirit or scope of the invention or sacrificing any of its advantages.

What I claim is:

- 5 In a building construction, the combination of a supporting structure, means as nails secured to said structure so as to leave a projected part of each nail, vertically and horizontally disposed tensile mediums as
- 10 wires secured to said nails by windings.

said wires being extended across said structure to form a net work, an adjustable device interposed between the secured ends of each and every tensile medium for regulating the tension thereof and a covering of cementitious material applied to said net work of wires.

In testimony whereof, I have hereunto signed my name.

JOSEPH R. WITZEL.
